UNITED STATES PATENT OFFICE.

EDWARD JOHN ANDERSON AND EARL JEROME HINTON, OF INDIANAPOLIS, INDIANA.

CHANNEL CUTTER.

Application filed September 11, 1928. Serial No. 305,178.

The present invention has reference to a tool especially designed for use by shoe repairmen, the primary object of the invention being to provide a tool for cutting the usual 5 thread channel in the sole of the shoe being repaired.

An important object of the invention is to provide a device of this character including a removable blade and a lateral guide, novel 10 means being provided for adjusting the guide with respect to the blade so that the channel will be formed evenly and at a predetermined point in spaced relation with the edge of the sole.

15 A still further object of the invention is to provide a tool of the hand operated type which may be moved along the sole of a shoe to accomplish the channel cutting with facility.

20 With the foregoing and other objects in view which will appear as the description proceeds, the invention resides in the combination and arrangement of parts and in the details of construction hereinafter described and 25 claimed, it being understood that changes in the precise embodiment of the invention herein disclosed, may be made within the scope of what is claimed, without departing from the spirit of the invention.

30 Referring to the drawing:

Figure 1 is a plan view of the device showing the manner of positioning the device on the sole of a shoe.

35 Figure 2 is a sectional view taken on line 2—2 of Figure 1.

Figure 3 is a side elevational view of the tool.

40 Figure 4 is a sectional view taken on line 4—4 of Figure 3.

45 Referring to the drawing in detail, the device includes an elongated body portion 5 which is provided with a shank that is extended into the handle indicated at 6.

A bore indicated by the reference character 50 7 is formed longitudinally of the body portion 5 and is disposed adjacent to the outer edge of the body portion, as clearly shown by Figure 2 of the drawing, the ends of the bore being open to permit the blade indicated at 8, to be positioned therein in such a way that the cutting end of the blade will extend beyond the outer end of the body portion so that it may accomplish its purpose, when the tool is moved over a shoe sole.

55 Extending through the body portion in

such a way that the inner end thereof will pass into the bore 7, is a securing screw 9 that engages the blade 8 to hold the blade in its positions of adjustment and to regulate the depth of operation of the blade.

The reference character 10 designates a guiding finger, and as shown, this guiding finger is of a length to extend beyond the outer end of the body portion 5 so that it will rub the outer edge of the sole to be secured and prevent a channel of an irregular character being formed. It will also be seen that due to this construction the blade may be held at a point a predetermined distance from the edge of the sole.

60 Adjusting screws indicated by the reference character 11 extend through openings in the guide finger 10 and are positioned in threaded openings of the body portion 5 so that as the adjusting screws are moved, the guide finger 65 may be adjusted towards or away from the body portion to insure the channel being cut the proper distance from the edge of the sole.

60 In order to insure an accurate operation of the device a lock screw 12 is provided, which lock screw extends through a threaded opening in the finger 10, the inner end of the lock screw resting in a recess formed in the body portion 5 with the result that after an adjustment has been made, the lock screw 12 85 may be operated to force the finger 10 laterally and set up a binding action between the adjusting screws 11 and the threads of the openings in which they move, locking the guide finger in its positions of adjustment.

90 The cutting ends of the blade 8 are substantially triangular in formation, so that they will dig into the surface of the sole and cut a substantially V-shaped groove or channel to receive the threads employed for securing the sole to the shoe.

95 From the foregoing it will be obvious that due to the construction shown and described, a channel may be readily and easily formed in the sole of a shoe at a point adjacent to the edge of the sole insuring a true channel for the reception of the thread employed in securing the sole to the shoe.

We claim:

100 A tool of the class described including a body portion having a bore disposed longitudinally thereof, a blade disposed within the bore, means for engaging the blade to secure the blade against movement within the bore, a guiding finger having one end thereof ex- 110

tended beyond the free end of the body portion, screws extending through the finger and through the body portion for adjusting the finger laterally with respect to the body portion, said body portion having a recess in one side thereof, and a lock screw extending through the finger and resting in the recess

to hold the finger in its positions of adjustment.

In testimony that we claim the foregoing ¹⁰ as our own, we have hereto affixed our signatures.

EDWARD JOHN ANDERSON.
EARL JEROME HINTON.
